INTERNAL COMBUSTION APPARATUS

Charles L. Boisset, New Orleans, La.

Application February 28, 1931. Serial No. 519,193

11 Claims. (Cl. 126—116)

This invention relates to improvements in interval combustion apparatus, and it consists of the constructions, combinations and arrangements herein described and claimed.

5 An object of the invention is to provide an internal combustion apparatus particularly adapted to the purpose of heating dwellings and other buildings, as well as the purpose of providing a heated fluid applicable to other and 10 possibly not allied purposes.

Another object of the invention is to provide an internal combustion apparatus which includes a part generally denoted the heat source which embodies provisions for commingling the products 15 of combustion of a burner with volumes of air for the purpose of producing a heated fluid to be circulated in a heating system or diverted to any other desired purpose.

A further object of the invention is to provide 20 a heating system for dwellings and the like, in which system the heat source and the instrumentalities connected with it comprise one of the outstanding features.

Other objects and advantages will appear in 25 the following specification, reference being had to the accompanying drawings in which

Figure 1 is a diagrammatic sectional view illustrating what is herein known as the vacuum system, the details of the heat source being 30 clearly shown.

Figure 2 is a sectional view of the heat source, illustrating slight modifications in internal structure, and showing a variation in the use of the heated fluid, namely for the purpose of heating 35 an oven.

Figure 3 is a diagram illustrating a further modification of both the heat source and heating system, the adaptation being to what is commonly known a hot air heating system for dwellings.

Figure 4 is a detail sectional view of a part of the fluid conduit in Figure 2, illustrating one type of thermostat capable of use in conjunction with the damper control.

45 One of the underlying purposes of the invention is to utilize a combustible fluid to the best advantage, so that there will be a minimum of loss of heat units by radiation, improper burning of the fuel etc., all to the end of producing a heated fluid capable of being conducted through conduits for heating dwellings either directly or indirectly, or for serving other purposes, for example heating an oven. In its general aspects the apparatus 1, herein known 55 as the heat source, is fundamentally the same

in each of the several forms of the invention disclosed, but in each form some necessary modifications are embodied, making the apparatus or heat source more appropriate to the specific use.

Attention is first directed to Figure 1 which 60 illustrates the apparatus 1 in conjunction with a vacuum heating system 2. The apparatus 1 comprises a casing 3 which obviously may be of any desired shape, this being surmounted by a cover 4 which comprises the foundation plate for a pair of concentric cylinders 5, 6, the cylinder 5 being the enclosure for a certain burner chamber later described.

It is not essential to the invention that the 70 members 5, 6 be cylindrical. In practice they may have other cross sectional shapes and will serve the purposes of the invention equally as well. The outer cylinder 6 is open at the top as at 7 so as to provide an ample entrance for 75 atmospheric air. Air is continuously drawn in at the entrance by the working of the system as presently appears, it being remembered that the system is of the so-called vacuum type.

The inner cylinder 5 has a top closure 8 which 80 has connection with a conduit 9 which leads to all parts of the heating system 2. While considering the heating system it may be pointed out that a radiator 10 is connected at one end with the conduit 9 as at 11, and at the other end with 85 a return pipe 12 which communicates with the inlet 13 of a centrifugal fan 14 or other blast forming means. This fan is revolved within a housing 15 by any suitable means, for example, an electric motor of suitable horsepower which 90 is not disclosed.

Returning to the concentric cylinders 5, 6, it 95 is noted in Figure 1 that these are stood at their lower edges in concentric annular depressions 16, 17 in the cover 4. The points of contact of the cylinders with the cover are intended to be made firm so that the cylinders will not move out of place when once erected. The annular space 18 between the cylinders 5, 6 has communication with the interior of the casing 3 through a series 100 of holes 19 in that part of the cover 4 appearing between the bottom edges of the cylinders.

The specific and probably obvious purpose of the holes 19 is to admit the atmospheric air originally received at the entrance 7, to a burner 105 20. The air supports the combustion of the fuel which in this instance is furnace oil. The oil is delivered to a nozzle 21 by a fuel pump 22 of any preferred design, this pump being operated in common with the fan 14 by a belt 23 or such 110

other driving connection as may be decided upon. The belt is applied to pulleys respectively on the fan and pump shafts.

The speeds of rotation of both the fan 14 and pump 22 will depend to a large extent on the particular types employed as well as the specific requirements of a given installation. However, one example of the speed ratios is 1750 R. P. M. for the fan 14 and approximately 1000 R. P. M. for the pump 22. In this particular installation the fan 14 is driven directly from the motor (not shown). The pulleys on the fan and pump shafts are of such ratios that the pump works about two-thirds the speed of the fan.

15 A bracket 24 appropriately supports the nozzle 21 in the center of a rather large aperture 25 in the top 26 of a bonnet 27. This bonnet is appropriately secured in an opening 28 of the required size in the cover 4.

20 There should be an air seal around the bonnet 27, that is to say in the joint between the bonnet and the opening 28. This confines all of the air admitted at the holes 19 to the central aperture 25 and to a radial series of angled outlets 29. The 25 intervening parts of the bonnet 27 occurring in the zone of the outlets 29 produce biased vanes which have the result of giving the air a swirling motion, tending to confine it in a somewhat compact volume within a burner chamber 30 into 30 the bottom of which the burner 20 is directed, said chamber therefore being the receiver means for the products of combustion.

This burner chamber, somewhat like its adjoining members, is a cylinder which is fixedly stood 35 on the cover 4. However, the instant relationship of the chamber 30 to the cylinders 5, 6 is eccentric because of the introduction of a pipe 31 which affords communication between the interior of the fan housing 15 with the interior of 40 the cylinder 5. This eccentric relationship is not necessarily adhered to in practice, and as a matter of preference would be replaced by a concentric relationship of all three cylinders. The advantage of such a relationship would be an 45 equal distribution of fluid in the cylinder 5 around the chamber 30. As observed in Figure 1, the top of the chamber 30 is open and communicates directly with the interior of the cylinder 5. The products of combustion are thus discharged directly 50 into the volume of air driven into the cylinder 5 by the fan 14, the mixture producing what is herein known as the heated fluid. The fan current past the open end of the chamber 30 aids in drawing out the products of combustion.

55 A flue 32 joins the pipe 31 at the general place of connection of the latter with the outlet of the fan housing 15. Some of the exhausted gases withdrawn from the system 2 by the fan 14 are discharged into the flue 32 and in turn to atmosphere, the remainder being driven into the pipe 60 31 for mixture with volumes of heated fluid and subsequent circulation in the system.

This partial elimination of exhausted gases and mixture of the remainder with volumes of 65 fresh air is a direct result of the adjustments of a damper 33 pivoted across the pipe 31. It can readily be understood that if the damper 33 were closed entirely, the suction set up at the inlet 13 of the fan housing would be of such a degree as 70 to compel a maximum induction of atmospheric air at the holes 19, bearing in mind that the suction in the return pipe 12 must be traced through the radiator 10, conduit 9, cylinder 5, chamber 30 and burner 20.

75 Under the same circumstance, the action of the

fan 14 would be to drive all of the so-called exhaust gases into the flue 32 and so out to atmosphere, remembering that the damper 33 is closed. In this respect the flue 32 provides a bypass.

This would obviously constitute a very inefficient operation, first from the standpoint of driving to atmosphere through the flue 32 large volumes of heated gases; and second from the standpoint of supplying the burner 20 with so much air as to blow the flame out. With these understandings it becomes necessary to adjust the damper 33 in order to arrive at an efficient balance of operation. Such an adjustment of the damper 33 is approximately half way between its fully open and closed positions. Remembering that the suction of the fan 14 is felt in the inner cylinder 5 it is easy to understand that considerable volumes of exhaust gases are drawn in at the pipe 31 to commingle in the cylinder 5 with a relatively small volume of atmospheric air received at the holes 19. Some of the exhaust gas will naturally escape at the flue 32, but this will be so inconsiderable as to not noticeably affect the economical operation of the apparatus.

100 By virtue of the fact that the chamber 30 contains a large flame it is apparent that the walls of the chamber will become very hot. The gases passing around the chamber 30 will be heated by the contact, soon to actually commingle with the gases evolved in the chamber 30 and discharged at the open top, all to the end of producing a heated fluid.

The inner cylinder 5 will also become heated, and inasmuch as the air passing down the annular space 18 comes in contact with the cylinder 5 said air will become preheated thus conserving the heat. The space 18 constitutes an air jacket which insulates the cylinder 5. As is common in practice, the fuel is ignited by a spark plug 34 which is supplied with high tension current from a suitable source 35. The spark plug is secured in the top 26 and assumes the position at the side of the nozzle 21, well out of the zone of the flame. In practice the actual flame appears about 3" from the tip of the nozzle, the intervening atmosphere being gaseous.

110 Attention is next directed to Figure 2 in which a number of parts are substantially like corresponding parts in Figure 1, and are therefore designated by corresponding numerals without 125 a repetition of the description. The chief differences reside in the nature of the system 2 and in the mode of control of the fluid within the casing 3.

The conduit 9, instead of leading to the radiators of a dwelling, leads to an oven 36 which is intended to be heated by the fluid. A pipe 37 conveys the exhaust fluid to atmosphere.

Instead of the burner 20 being directly supplied with air from the holes 19 the bonnet 27 is entirely closed off underneath from the casing 3 by means of a branch or bypass 38 extending off to one side of the pipe 31. This pipe simply connects the interior of the inner cylinder 5 with the outlet of the fan housing 15. There is no equivalent of the flue 32, unless it is the pipe 37, and the housing inlet 13 communicates directly with the interior of the casing 3, rather than with an exhaust return pipe as before.

145 Situated in the pipe 31 in such a manner as to control the pipe as well as the branch 38 is a pair of dampers 39, 40. The damper 39 acts in the capacity of a throttle while the damper 40 acts as a deflector. The pivots of these dampers have levers 41, 42 extending off to a place of con-

nection with a rod 43 which extends out from the arm 44 of a thermostat 45 (Fig. 4).

This thermostat may comprise any known stack type, but for illustration is shown as consisting of a bi-metallic strip wound in a spiral (Fig. 4) anchored at one end as at 46 and connected at the other to a revoluble shaft 47, one end of which carries the arm 44 already referred to. A weight 48, adjustable on an extension of 10 the arm, balances the rod 43 depending from the opposite end of the arm and therefore enables the operation of the thermostat 45 (Fig. 4) with the utmost freedom.

Assume the heat of the fluid discharged into 15 the conduit 9 as being excessive. The resulting expansion of the bi-metallic strip 45 (Fig. 4) causes a rotation of the shaft 47 counter-clockwise, with a consequent lowering of the rod 43, a turning of the throttle 39 toward its erect 20 position and a turning of the deflector 40 toward a closing position in respect to the branch 38.

The effect in operation is an increased supply 25 of air through the pipe 31 to the interior of the cylinder 5 but the maintenance of a substantially constant volume of gas to the burner 20. The pump 22 operates uniformly to supply the nozzle 21 with a substantially constant volume of oil, and since there is no ordinary variation in the oil supply it is obviously necessary to keep 30 the air supply by way of the branch 38 substantially constant in order to maintain a given intensity of the flame.

The result of the increased volume of air admitted by way of the pipe 31 will proportionately cool the gas supplied to the conduit 9. 35 The resulting contraction of the bi-metallic strip 45 will rotate the shaft 47 clockwise, raise the rod 43 and reinstate the dampers 39, 40 in more or less the former position. Should the temperature 40 of the fluid in the conduit 9 drop to lower degrees, there would be a still further closing of the throttle 39 to shut off more of the outside air from the cylinder 5 and so give predominance to the heated gases discharged from 45 the chamber 30.

But conformable with the further closing of the throttle 39 the deflector 40 moves out farther toward the left so as to compensate by its extension for the reduced volume of air permitted to escape past the throttle 39. The result of the action of the deflector 40 is to keep substantially constant the volume of air directed to the burner 20. Under any circumstance the air discharged by the pipe 31 into 55 the cylinder 5 is deflected toward the chamber 30 by a baffle 5^a situated approximately as shown in Figure 2.

Reference is next made to Figure 3. This is a system intended for use in dwellings having 60 what is known as a hot air heating system. Such parts as correspond with the apparatus 1 already described are identified by corresponding numerals, but the modified parts comprise the following:—A pipe 49 leads to a register (not shown) to supply a room with heated air, while a pipe 50 conducts cooled air from the room to a container 51 with the outlet 52 of which the pipe 49 connects and in which all of the heating apparatus is situated.

70 A motor driven fan 53 sets up a circulation as best denoted by arrows a. The fan 14 sets up a current in the pipe 31 as before, causing a discharge of the heated fluid into the conduit 9 largely on the principle of the system in Figure 75 2. The pipe 9, now actually comprises a mani-

fold, between which and another manifold 54 a series of tubes 55 extends. The heated fluid is circulated as denoted by the arrows b.

Atmospheric air is admitted to a chamber which is the equivalent of the casing 3 through an air inlet tube or opening 56. This air is supplied to the burner 20. A flue is arranged concentrically of the tube 56, and since this agrees in purpose to the flue 32 in Figure 1 it is similarly identified 32. The tube 56 is of appreciable length and not so much larger in diameter than the flue 32 which it encloses. The resulting constricted air passage confines the incoming air to close quarters and is hereby pre-heated before admission to the container 51. The degree of preheating is governed by a damper in the pipe 31. The heat content of the flue 32 increases as the damper is tilted toward the flue, and in practice best positions of the damper are established whereat proper volumes are directed into the cylinder 5 and into the flue 32. Of necessity only fresh air can be circulated in the pipes 49, 50 and the room of the dwelling with which these connect. The heated fluid is confined to the circulatory system comprising the 100 pipes 31, 9, tubes 55 and manifold 54.

Staggered baffles 57 extend toward the tubes 55 from opposite sides so as to lead the fresh air (arrows a) over a tortuous course and so insure a thorough exchange of heat. The uppermost one 105 of these baffles extends out from a wall 58 which is a continuation of the left side of the casing 3. This wall also constitutes a baffle, inasmuch as it aids in compelling the fresh air stream to pass down beside the cylinder 5 before reaching the 110 outlet 52.

In operation, the system in Figure 3 will be largely on the order of that in Figure 1. The fan 14 propels the gas and maintains a flow 115 through a conduit system which, instead of including the radiator 2 now includes the tubing 55 which is a substantial equivalent.

However, instead of having the tubing 55 situated off in a room by itself, it is confined to the container 51 (Fig. 3) in common with the rest 120 of the apparatus, to be contacted by an independent current of air which is independently circulated through the remote room by the fan 53. Thus it will be seen that, as previously stated, although each modification involves peculiarities of construction yet an underlying principle prevails to the end of mixing the high temperature products of combustion with volumes of air to produce a heated fluid, said fluid being later employed to warm other volumes of fluid contacting the conduit system by which the heated fluid is conducted.

While the construction and arrangement of the improved internal combustion apparatus is that of a generally preferred form, obviously modifications and changes may be made without departing from the spirit of the invention or the scope of the claims.

I claim:—

1. A heating system comprising a conduit, a cylinder with which one end of the conduit is connected, a fan housing having an inlet for atmospheric air and an outlet pipe connected with the cylinder, a fan revoluble in the housing for discharging air through the pipe into the cylinder, a fuel burner directed into the cylinder, a branch extending off from the pipe and carrying the burner, dampers in the pipe respectively adjacent to the inlet to the branch and to the outlet of the fan, and a thermostat situated in the con- 140 nection with the branch.

- duit having connecting means for simultaneously operating both dampers.
2. A heat source apparatus comprising an open outer cylinder, an inner cylinder spaced therefrom having a top closure communicable with a conduit, a casing, a foundation plate providing a mounting for the cylinders, covering the casing and having a hole providing communication of the casing with the space between the cylinders, a fan housing having a pipe connected with the inner cylinder and an inlet connectible with said conduit to set up a suction in the inner cylinder, a fuel burner mounted on said plate including a bonnet having air outlets supplied with air from said hole, and an open ended chamber situated in the inner cylinder on said plate around the burner bonnet.
3. A heat source apparatus comprising an open ended outer cylinder, an inner cylinder spaced from the outer cylinder, a top closure for the inner cylinder connectible with a conduit, a casing, a foundation plate covering the casing, providing a mounting for the cylinders and having a hole providing communication of the casing with the space between the cylinders, an open ended chamber mounted on said plate within the inner cylinder, a fan housing in the casing having an inlet communicating with the inside of the casing and an outlet pipe communicating with the inside of the inner cylinder, a branch at one side of said pipe, a fuel burner carried by said branch and being directed into the chamber, and a pair of dampers respectively in said pipes and adjacent to the inlet to the branch.
4. In a heating system having a burner chamber open at one end, a burner fixed at the opposite end of the chamber to fill the chamber with its products of combustion, a cylinder spaced eccentrically around the burner chamber having said open end in communication therewith, and a conduit with which the end of the cylinder adjacent to said open end is connected; a blower connected to the other end of the cylinder at the large part of the eccentric space, setting up current through said large part alongside of the burner chamber and past its open end to draw out the products of combustion and drive them into the conduit.
5. A heating system comprising a burner chamber having an undiminished opening at one end, a cylinder spaced around the burner chamber having said opening in immediate communication therewith, a common bottom for the burner chamber and cylinder closing off one end of said cylinder, a burner fixed in said bottom to discharge its products of combustion into the burner chamber, a blower having its outlet attached to the common bottom to discharge its current upwardly thru the bottom into the cylinder space in a substantially straight path beside the burner chamber and past said opening to draw out the products of combustion, and a conduit with which the other end of the cylinder is connected to receive said current and the commingled products of combustion.
6. A heating system comprising a burner chamber having an undiminished opening at one end, a cylinder spaced around the burner chamber having said opening in immediate communication therewith, a common bottom for the burner chamber and cylinder closing off one end of said cylinder, a burner fixed in said bottom to discharge its products of combustion into the burner chamber, a blower having its outlet attached to the common bottom to discharge its current upwardly thru the bottom into the cylinder space in a substantially straight path beside the burner chamber and past said opening to draw out the products of combustion, and a conduit with which the other end of the cylinder is connected to receive said current and the commingled products of combustion.
7. A heating system comprising a container, a circulatory system within the container comprising a cylinder, a conduit communicating therewith, a tube communicating with the conduit, a manifold communicating with the tube and a pipe connecting the manifold with said cylinder, a fuel burner discharging products of combustion into the cylinder, said container having an opening admitting atmospheric air to a part of said container to supply the burner and produce a heated fluid, a fan in said system to circulate the heated fluid, a bypass connecting the discharge side of the fan with the atmosphere through said opening, and means in the pipe to govern the discharge from the fan to variably deflect said discharge into the bypass.
8. A heating system comprising a container, a staggered-baffle arrangement in the container including a wall separating said arrangement from a space within the container, a plural-tube radiator transversely of said baffle arrangement which defines a devious air course around the radiator, air inlet means at one side of the container and a fan for driving air through said course over the wall into said space, an outlet pipe leading from said space, a burner apparatus located in said space comprising a conduit connected with one end of the radiator for supplying hot gas, a manifold connected with the other end of the radiator for receiving the hot gas, a blower in connection with the manifold for driving the hot gas back into the burner apparatus, and means to variably deflect some of the hot gas from the last blower away from the burner apparatus.
9. A heating system comprising a container, a staggered-baffle arrangement in the container including a wall separating said arrangement from a space within the container, a plural-tube radiator transversely of said baffle arrangement which defines a devious air course around the radiator, air inlet means at one side of the container and a fan for driving air through said course over the wall into said space, an outlet pipe leading from said space, a burner apparatus located in said space comprising a conduit connected with one end of the radiator for supplying hot gas, a manifold connected with the other end of the radiator for receiving the hot gas, a blower in connection with the manifold for driving the hot gas back into the burner apparatus, means to variably deflect some of the hot gas from the last blower away from the burner apparatus, a flue into which said hot gas is deflected, and a tube around the flue for admitting atmospheric air to the burner apparatus, said tube being of appreciable length and defining a constricted air passage.
10. In a heating system, a burner apparatus for producing hot gas, a pipe leading to the burner apparatus and constituting part of a hot gas-circulating system, a flue leading off from said pipe to atmosphere, an air inlet tube around said flue for supplying the burner apparatus with air,

said tube being of appreciable length and defining a constricted air passage around the flue, and a damper in the pipe to govern the flow of the hot gas as regards said apparatus and flue, the degree 5 of preheating of the air in said tube depending on the tilting of the damper toward said flue.

11. A heating system comprising a container and means to circulate fresh air therethrough, a circulatory system within the container comprising 10 a cylinder, a conduit communicating therewith, a tube communicating with the conduit, a

manifold communicating with the tube and a pipe leading off from the manifold, a fuel burner discharging products of combustion into the cylinder, said container having an opening admitting atmospheric air to a part of said container to supply the burner and produce a heated fluid, a fan in said system with which the pipe is connected to propel the heated fluid, and a flue connecting the discharge side of the fan with the atmosphere through said opening. 84
